UNITED STATES PATENT OFFICE

ORDA D. NUTTER, OF PARKERSBURG, WEST VIRGINIA, ASSIGNOR TO ACME FISHING TOOL CO., OF PARKERSBURG, WEST VIRGINIA, A CORPORATION OF WEST VIRGINIA

ROTARY TRIP SPEAR

Application filed June 6, 1928, Serial No. 283,358. Renewed August 2, 1930.

My present invention relates to a rotary trip spear as used for pulling casing sections from a well by engagement with the inside thereof.

5 The invention contemplates the provision of a spear of the above type, having a head adapted to be attached to a tool string, said head carrying a body, both of these elements being provided with an axial bore so as not to stop the flow of slush fluid into and out of the hole.

10 The upper portion of the body is provided with enlarged angular slip seats engaged by a plurality of slips having toothed exterior faces adapted to engage the interior periphery of the casing being pulled. The rear face of the slips and the seat on the body have the same angularity in order that the toothed face of the slip may always be presented parallel to the inner face of the casing. Each slip is retained in place at its top by an overhanging bell portion of the head, and at its bottom by a retainer rotatably carried on a trip sleeve mounted on the body.

15 25 The trip sleeve is capable of restricted longitudinal and rotary movement in relation to the body, this movement being limited by a bayonet joint between the parts.

30 Surrounding the lower portion of the trip sleeve is a friction spring assembly of the basket type merely held against displacement at the top by the slip retainer, and at the bottom by a cone nut on the bottom of the body.

35 40 The spring assembly comprises upper and lower collars with strip spring elements therebetween and rigid adjusting screws connecting the two collars. Movement of the collars toward each other under action of the screw members cause the spring strips to be bowed outwardly and thus grip the casing section with increased friction, or within limits enable the spear to be used with different weights of casing.

45 50 The cone nut is likewise provided with an axial bore so that the entire spear is hollow from top to bottom.

The invention further consists of the novel arrangement, combination and construction of parts more fully described hereinafter and

shown in the accompanying drawings, in which:

Fig. 1 is an elevation of the spear with the slips disengaged.

Fig. 2 is a similar view showing the slips 55 engaging the casing.

Referring now to the embodiment illustrated, I have shown the head at 1, having a truncated threaded cone 2 by means of which attachment may be made to the tool string 60 or rotary tool joint (not shown).

Threaded to the head 1 is an elongated body 3 threaded to the head as at 4 and keyed at 5. The lower portion of the head 1 is provided with an overhanging bell 6 forming a space between it and the body 3 to hold the upper portion of slips as will be more fully hereinafter described.

Below the head, the body enlarges angularly to form slip seats adapted to receive 70 the rear face of a plurality of slips 7. The angularity of the slip seat and rear face of of the slip is the same so that downward movement of the slip causes the same to move outward uniformly.

75 That portion of the body forming the slip seats is broken by elements 8 located between slips and engaging the side walls thereof. These members effectively prevent rotation of the slips about the body.

80 The outer face of each slip as shown is grooved or toothed in two directions as at 9 and 10, but is not limited to this construction. This configuration prevents the movement of the slip in relation to the casing section, 85 and permits unscrewing of the casing in the well by using the spear or a left handed drill string.

85 90 The upper portion of the slip 7 has a reduced extension 11 which is located between the bell 6 of the head and the body 3. A somewhat similar lower extension 12 is provided which is located between the body 3 and an upwardly extending wall 13 of a slip retainer 14.

95 The retainer 14 projects beneath an undercut shoulder of the body as at 15 and carries a member 16 threaded to the part 14 which in turn engages beneath a flange 17 in the trip sleeve 18. Between the bottom of the 100

part 14 and the top of the sleeve 18, ball bearings 19 are held so that the slip retainer assembly is secured to the trip sleeve yet capable of ball bearing rotation thereon.

5 The sleeve 18 is capable of limited rotary and longitudinal movement in relation to the body 3 due to the provision of a screw 20 riding in a slot having legs 21 and 22.

10 It will be obvious that as long as the screw 20 occupies the leg 22 of the slot, there can be no longitudinal movement between body 3 and trip sleeve 18. When however the body is slightly rotated so that the screw 20 may occupy leg 21 of the slot, the body may be moved upwardly in relation to the sleeve. 15 This separates the bell 6 of the head 1 and the part 14 of the slip retainer assembly. The angular wall of the slip seats on the body, thus pushes the slips outwardly against the interior face of the casing section, the teeth of the slips biting thereinto.

20 Located beneath the slip retainer assembly and surrounding the trip sleeve is a friction spring mechanism of the basket type. This 25 mechanism comprises an upper collar 23, a lower collar 24 joined by screw members 25 by means of which the collars may be made to move toward and away from each other.

Secured to the collars 23 and 24 are strip 30 springs 26 which are bowed to any desired extent by adjustment of the screws 25. The entire spring assembly is freely rotatable about the sleeve 18 and rests upon a cone nut 27 screwed into the bottom of the body 3.

35 An axial bore 28 passes completely through the entire device from threaded cone 2 to cone nut 27 so that the flow of slush fluid into and out of the well will not be prevented.

40 In operation, the friction spring assembly is so adjusted as to engage the casing to such a degree that the weight of the spear will be supported by this frictional contact between spring and casing. The screw 20 occupies the leg 22 of the slot. The tool is now lowered into the well, the rounded nose of 45 the cone nut guiding the spear into the casing to be drawn.

50 As soon as the spring assembly engages the casing, further lowering of the spear, causes the body and attached parts to move downward without the spring. As a consequence of this action, the spring assembly engages the shoulder 17a of the trip sleeve, and due to the fact that this shoulder projects 55 slightly below the bottom of the slip retainer assembly, the upper collar 23 is spaced from the slip retainer and the entire weight of the tool string is carried upon the friction spring assembly. Above this assembly however, there is the ball bearing joint so that the spear body and associated parts may rotate freely within the basket spring.

60 The spear may be forced down however, into the casing until the slips are at the desired location.

Clockwise movement of the spear head will now cause the screw 20 to leave the leg 22 of the slot and pass into leg 21.

Upward movement of the spear then causes the slip seats in the body to force the slips 70 out against the casing section, and the toothed surfaces of the former bite into the latter. The casing may thereupon be withdrawn.

75 The spear may be lowered into the well with screw 20 occupying the leg 21 of the slot, in which case when the slips come in contact with the casing they are elevated on the body causing them to contract and permitting them to enter the casing ready to engage the casing by upward movement of the spear as 80 described above.

To release the spear from the casing, the spear is lowered which causes the slips to disengage the casing. This movement is continued until the screw 20 is at the bottom of 85 the leg 21 in the slot.

90 Counter clockwise movement of the spear body places the screw in the slot 22 and thus locks the slips in their disengaged position, thus permitting the withdrawal of the spear from the casing. The spear can be made to engage or release the casing at will at any desired point within the casing and without withdrawing the spear to reset it.

95 The extent of the threads of the cone nut 27 is such that when the cone nut is entirely in place, the slip retainer and trip sleeve cannot be lowered far enough to completely release the ends of the slips. Thus by keeping the cone nut 27 in place as by pin 29, it is 100 impossible to lose a slip in the hole.

I claim:

1. A trip spear comprising a head and a body, a series of slips engageable with the body, a slip retainer carried by a trip sleeve, and a friction spring for carrying the weight 105 of the spear in a casing, the retainer being freely rotatable relative to the slips.

2. A trip spear comprising a body, a series of slips engaging the body, a slip retainer freely rotatable about the body, a trip sleeve carried by the body, the sleeve and retainer 110 engaging each other in a ball bearing joint and spring means to prevent rotation of the trip sleeve relative to the body.

3. A trip spear comprising a body, a series of slips engaging the body, a slip retainer and a trip sleeve carried by the body, a flexible friction spring carried by the sleeve to support the weight of the spear in a casing 120 and means to vary the flexure of the spring.

4. A trip spear comprising a head and a body, a series of slips underlying the head and engaging the body, a slip retainer underlying a shoulder on the body, a trip sleeve 125 engaging the retainer, ball bearings between the sleeve and the retainer, a friction spring assembly surrounding the sleeve and underlying the same to support the weight of a spear in a casing.

5. A trip spear comprising a head and a body, a series of slips underlying the head and engaging the body, a slip retainer freely rotatable about the body, a trip sleeve carried by the body, the sleeve and retainer engaging each other in a ball bearing joint, and means for preventing rotation of the slips on the body and spring means to prevent rotation of the trip sleeve relative to the body.
- 10 6. A trip spear comprising a head and a body, a series of slips underlying the head and engaging the body, a slip retainer freely rotatable about the body, a trip sleeve carried by the body, the sleeve and retainer engaging each other in a ball bearing joint, and means for spacing the slips apart in the body and spring means to prevent rotation of the trip sleeve relative to the body.
- 15 7. A trip spear comprising a body, slips thereon, means to retain the slips about the body, means to trip the slips into inoperative position, and a swivel joint between the trip means and the slip retaining means.

In testimony whereof, I affix my signature.
